INK DISPENSING APPARATUS
Harvey D. Smalley, Jr., Perham, Minn.
Filed Oct. 24, 1960, Ser. No. 64,378
2 Claims. (Cl. 222—400.7)

This invention relates to ink-dispensing apparatus for use with printing presses and more particularly to pneumatic pressure type ink supply mechanism for use in supplying ink to printing press fountains.

An object of this invention is to provide a novel pneumatic type ink-dispensing apparatus, of simple and inexpensive construction, for use in supplying ink to printing press fountains.

Another object of this invention is to provide a novel pneumatic type ink-dispensing apparatus including a pressurized housing having a readily removable ink receptacle disposed therein connectable with the fountain of a printing press in fluid conducting relation therewith to permit ink within the receptacle to be dispensed therefrom into the printing press fountain without any ink directly contacting the interior of the housing, thus obviating the need for cleaning the latter.

A still further object of this invention is to provide a novel pneumatic type ink-dispensing apparatus for use with printing presses and including a pressurized housing for receiving a conventional open-topped ink container disposed therein, the housing having a readily removable cover including means for facilitating quick connection thereof to the ink fountain of a printing press, thus permitting rapid and efficient change of different kinds of ink for use with the printing press.

These and other objects and advantages of my invention will more fully appear from the following description made in connection with the accompanying drawing wherein like character references refer to the same or similar parts throughout the several views, and in which:

FIG. 1 is a diagrammatic end elevational view of the conventional printing press incorporating my novel ink-dispensing apparatus;

FIG. 2 is an enlarged vertical section through the ink-dispensing apparatus showing details thereof;

FIG. 3 is an enlarged vertical sectional view similar to FIG. 2 through the ink-dispensing apparatus including a slightly modified form of cover attachment means and illustrating a modified ink container disposed therein; and

FIG. 4 is an enlarged vertical sectional view similar to FIG. 4 through the ink dispensing apparatus and illustrating a still further modified form of the ink container disposed therein.

Referring now to the drawings and more specifically to FIG. 1 it will be seen that one embodiment of my invention is shown incorporated in a printing press 10 which may be of conventional construction and includes side supports or standards 11. An elongate transversely extending pick-up or ink-distributing roll 12 extends between and is journaled for support on the side supports 11 for rotation relative thereto. Printing press 11 is also provided with printing rolls 13 and 14 which are also rotatably supported on the side supports or standards 11 and the pick-up and printing rolls are arranged to be rotated at relatively fast peripheral speed in a manner well known in the art.

The uppermost portions of the side supports 11, as best seen in FIG. 1, are provided with brackets 15 each having a set screw 16. A disposable inking mechanism, designated in its entirety by the reference numeral 17 and more fully described and illustrated in my co-pending application, Serial Number 30,512 extends between and is detachably connected to the brackets 15 by means of the set screw 16. This disposable inking mechanism 17 includes

2

an elongated substantially tubular fountain member 18 which is formed of plastic material and which has one end thereof closed as at 19. Although not shown in the drawing, fountain member 18 is also provided with a plurality of longitudinally aligned discharge apertures each of which is in communicating relation with the interior of the fountain member. Inking mechanism 17 also includes means for controlling the flow of ink from the elongate fountain member 18 and this means is comprised of a valve mechanism 20 which is in the form of an elongate sleeve formed of flexible impervious plastic material.

This sleeve 20 although not shown in the drawings of the instant application but clearly described in my co-pending application is provided with a plurality of longitudinally aligned apertures each being disposed closely adjacent the apertures of the elongate fountain member 18. A plurality of tensioning means in the form of threaded bolts 21 is carried by a fountain member 18 and engages the sleeve 20 for varying the tension on the sleeve 20 which in turn controls the flow of ink through the apertures in the fountain member and thereafter through the apertures in the sleeve in a manner clearly described in my co-pending application.

As clearly described in my co-pending application, the inking mechanism described therein permitted an operator to change from one can of ink to another without requiring the time consuming washing and cleaning operation of the printing press. I have also provided a uniquely constructed ink-dispensing mechanism which permits quick change of the kind of ink for the printing press while obviating the need of a cleaning or washing operation.

This uniquely constructed ink-dispensing apparatus designed in its entirety by the reference numeral 22 includes a pressurized housing 23 which in the embodiment shown is provided with a bottom 24 having upstanding peripheral walls 25 rigidly formed therewith. Housing 23 may be formed of any suitable rigid material such as steel or the like and it will be seen that this pressurized housing will be supported adjacent one side of the printing press by a bracket 11a secured to one of the standards 11, as best seen in FIG. 1. The upper marginal portion of the peripheral walls 25 of the housing is provided with an out-turned annular flange 25a.

Housing 23 is provided with a removable cover 26 having a plurality of over center locking means 27 carried thereby having suitable hooks 27a for engagement with the outturned annular flange 25a of the peripheral walls 25. A gasket 28 is interposed between the cover and the upper edge portion of the peripheral walls 25 to provide a fluid seal therat. When the cover 26 is secured to the peripheral walls of the housing 23 a substantially closed pressure chamber 23a is defined within the interior of the housing.

A threaded inlet 29 is carried by the cover 26 and is adapted to be connected to a source of air under pressure for supplying air to the chamber 23a. The pressurized housing 23 is also provided with a threaded discharge outlet 30 which in the embodiment shown extends upwardly from the cover 26 of the housing.

Referring again to FIG. 2, it will be seen that an ink receptacle 31 is positioned within the chamber 23a of housing 23 and this ink receptacle is of a size and shape of those normally used in the printing industry. The ink normally used in the printing industry, as is well

known in the art, is produced in one to five pound cans and it is pointed out that the container or receptacle 31 may also be formed of metal in the manner of the conventional ink cans or the receptacle may be formed of plastic or other rigid material. In the embodiment shown, the receptacle 31 includes a bottom 32 and upstanding peripheral walls 32a and when the receptacle is positioned within the housing 23 the top thereof is

removed so that the ink within the receptacle will be subjected to the pneumatic pressure within the chamber 23a.

An elongate conduit 33, as best seen in FIG. 2, extends through the discharge outlet 30 of the housing 23 in fluid-sealing relation therewith. It will be seen that a sealing or packing nut 34 threadedly engages the threaded outlet 30 and urges an annular sealing gasket 34a into engagement with the external surface of the conduit 33 so that a fluid seal is formed thereat and which precludes the escape of air therefrom. It will be noted that conduit 33 extends into the chamber 23a and is insertable into the ink receptacle 31 so that the ink may flow through the conduit once pressure is supplied to the chamber 23a. Conduit 34 is preferably formed of substantially rigid material such as plastic or the like and projects upwardly from the packer nut 34 as best seen in FIG. 2.

The other end of conduit 34 has a coupling carried in fluid-sealing relation thereby and this coupling 35 is connected to the end of the disposable fountain 18 in fluid-conducting relation therewith.

Referring now to FIG. 1, it will be seen that the threaded inlet 29 is connected to a conduit branch 36; a three way valve 37 is disposed in fluid-conducting relation with respect to conduit 36 and this valve 37, as described in my co-pending application, also includes a handle actuator 38 for actuating the flow of air therethrough. Valve 37 is also disposed in fluid-controlling relation with respect to a relief conduit 39 whereby air may be discharged therethrough and is interconnected to an air pressure regulator valve mechanism 40 having an indicator gauge 41 associated therewith and which is interposed in fluid-controlling relation with respect to a conduit 42 which in turn is connected to a source of air under pressure (not shown). The air pressure to the ink-dispensing apparatus 22 is controlled by the air pressure regulator 40 and the actuator handle 38 of valve 37 permits the pressure to be turned on and off by moving the same between operative and inoperative positions.

In operation, an ink receptacle 31 having the top thereof removed will be disposed within the chamber 23a of housing 23 and the conduit 34 will be inserted through the inlet 30 of the cover 26 and into the ink receptacle 31. It has been found that when the conduit 33 is extended or inserted into the receptacle 31 a substantial fluid seal is formed around the exterior surface of the conduit by means of the packing nut 34 and sealing gasket 34a so that air will not escape from the interior of the chamber 23a. The cover 26 when connected in sealing relation with the housing 23 will also be connected to the conduit branch 36 by means of the threaded inlet 29. The air pressure regulator mechanism 40 will be set to permit a predetermined amount of air to flow to the chamber 23a and the actuator handle 38 for valve 37 is moved from an off position to an on position to thereby permit air to flow into the interior of housing 23. This pneumatic air pressure within the chamber 23a will cause the ink within the open top receptacle 31 to flow outwardly through the conduit 33 and into the elongate fountain member 18. The ink will thereafter pass outwardly through the discharge apertures in the fountain and through the apertures in the sleeve 20 and onto the pick-up roll 12. If it is desirable to change the kind or color on the ink, the valve 38 will be moved to an inoperative position and the cover 26 of the housing will be removed therefrom. The ink receptacle 31 may be quickly removed and a new ink receptacle connected in fluid-conducting relation with the conduit 33. It is pointed out, however, that the elongate ink fountain 18 and the conduit 33 which are of the disposable type will be first disposed of which may be accomplished in a rapid manner as described in my co-pending application. The printing press will then be arranged for printing with a

different kind of ink without necessitating the washing of the pressure chamber 23a.

Referring now to FIG. 3, it will be seen that I have provided a different locking or retaining mechanism for securing the cover 26 in sealing relation upon the angular flange 25a of the housing 23. The locking means shown in FIG. 3 is generally designated by the reference numeral 50 and this locking means includes a plurality of elongate threaded elements 51, each having its respective lower end disposed between a pair of radially extending ears 52, fixedly connected to the outer circumferential surface of the peripheral walls 25 of the housing 23. A pivot pin 53 secures the lower terminal portion of the threaded element 51 to its associate pair of ears 52 to permit the elongate threaded element to swing into and out of locking position with the cover 26 and annular flange 25a. Actually each of the threaded elements 51 will be positioned within a slot 25b formed in the annular flange 25a and a registering slot 26a formed in the cover 26 when the threaded element is in locking position and a wing nut 54 threadedly engages the upper terminal portion of the threaded element 51 to cause the cover 26 to be urged into sealing relation with the annular flange 25a.

A modified ink container 61 is shown disposed within the housing 23 illustrated in FIG. 3 and this container includes a lower or bottom wall 62 and upstanding peripheral wall 62a. This container is also provided with a cover 63 which is secured to the upper peripheral edges 30 of the peripheral wall 62a and this cover 63 is provided with a pair of frangible knockout portions 64 and 65, each of which are formed by slightly scoring the cover 63 in annular fashion to define the respective knockout portions. These frangible portions may also be constructed of the same materials as the cover but having a thickness substantially less than the thickness of the cover. This construction of the portions 64 and 65 also renders them readily frangible. In use, the knockout portions 64 and 65 will be readily opened or knocked out and the conduit 34 will be extended through the opening 64 while the opening defined by the removed knockout portion 65 will permit the air pressure to be passed into the interior of the container 61 to thereby force the ink fluid upwardly through the tube or conduit 34 in a manner to preclude any spillage of the ink into the interior of the pressurized housing 23. Again it will be noted that this arrangement permits the pressurized housing to be used successively with containers having different kinds of inks without necessitating the washing of the interior of the housing.

Referring now to FIG. 4, it will be seen that I have provided a still further embodiment of the ink container which is readily adaptable for use with my inking mechanism and this container 71 also includes a bottom wall 72 and an upstanding peripheral wall 72a and is adapted to contain a predetermined quantity of ink therein. Actually some of the inks used in printing vary in viscosity and some types are of relatively thick consistency. In order to get effective discharge of such ink from the container 71 through the conduit 34, I have provided the container 71 with a cover 73 having an upturned annular flange 74 which engages the inner circumferential surface of the container 71 for sliding movement relative to the upstanding circumferential walls 72a. This cover is also provided with a knockout portion formed of frangible material which defines an opening 75 when removed therefrom. A sealing means 76 in the form of a small O-ring may be provided to effectively seal the area around the knockout portion. In use the cover 73 will be left in place and conduit 34 will be inserted through the knockout portion 75 somewhat in the manner of the container illustrated in FIG. 3. Upon the introduction of air under pressure through the inlet 29, the cover 73 will be forced downwardly by the air pressure thus causing the ink to be thereafter forced upwardly

outwardly through the conduit 34 and through the ink dispensing fountain. Thus, it will be seen that through the use of my uniquely constructed ink containers and pressurized ink dispensing apparatus inks which vary in viscosity may be readily dispensed without any spillage 5 causing ink in subsequent requirement of cleaning of the apparatus in the event it is desirable to use a different color or kind of ink at some subsequent time.

It will be seen from the foregoing description that I have provided a novel ink-dispensing apparatus of the 10 pneumatic pressure type which permits rapid and quick changing from one kind of ink to another without requiring washing or cleaning of the ink-dispensing apparatus.

It will also be seen from the preceding paragraphs that my unique ink-dispensing apparatus is arranged and constructed so that the ink reservoir is actually comprised of a container in which the ink is shipped thus obviating the 15 need of troublesome handling and transfer of the ink.

It will also be noted that my unique ink-dispensing apparatus also includes ink receptacles having frangible portions for ready breaking thereof to permit the ink to 20 readily discharge for the container when subjected to pneumatic pressure.

It will, therefore, be seen a great saving of time and labor may be obtained through the use of my novel ink-dispensing apparatus thus permitting the printing press 25 to be used in a more efficient manner than heretofore known.

It will, of course, be understood that various changes may be made in the form, details, arrangement and proportions of the various parts without departing from the 30 scope of my invention.

What is claimed is:

1. Ink dispensing apparatus for use with printing press machines, said apparatus comprising 35
  - an open top housing defining a pressure chamber there- within,
  - a cover member detachably secured to said housing in fluid sealing relation therewith to close the open top thereof and to thereby seal the pressure chamber 40 from the exterior,
  - said cover having a discharge outlet opening therein communicating with said pressure chamber,
  - an inlet coupling element secured to said cover in com- 45 municating relation with said chamber and being connectable to a source of air under pressure to permit a constant flow of air under predetermined pressure to be supplied to said chamber,
  - a hollow, open-top disposable receptacle positioned 50 within said housing and containing a supply of ink therewithin,
  - an elongate vertically disposed conduit projecting

through said discharge outlet and having its lower end portion extending into said receptacle, the upper end portion of said conduit being connectable directly to the ink fountain of a printing press in fluid communication therewith whereby ink within said receptacle is caused to flow directly through said conduit in response to the positive air pressure exerted on the surface of the ink supply within the receptacle.

2. A printing press having in combination an ink fountain, 10
  - an ink dispensing apparatus including an open top housing defining a pressure chamber therewithin, means for mounting said housing on said printing press in close proximity to said ink fountain,
  - a cover member detachably secured to said housing in fluid-sealing relation therewith to close the open-top thereof and to seal the pressure chamber from the exterior,
  - said cover having a discharge outlet opening therein communicating with said pressure chamber,
  - an inlet coupling element secured to said cover in communicating relation with said chamber and being connectable to a source of air under pressure to permit a constant flow of air under predetermined pressure to be supplied to said pressure chamber,
  - a hollow open-top disposable receptacle positioned within said housing and containing a supply of ink therein,
  - an elongate vertically disposed conduit projecting through said discharge outlet and having its lower end portion extending into said ink containing receptacle, and having its upper end connected directly to the ink fountain of the printing press in fluid communication therewith,
  - a cover slidably engaging the inner wall surfaces of the ink containing receptacle to close the open top of the same,
  - said cover including a frangible portion through which the lower end portion of said conduit projects, and said cover being downwardly slidable into said receptacle in response to air pressure exerted on the upper surface thereof to force the ink within said receptacle to flow through said conduit and into the printing press ink fountain.
